PULL TOY

Michael Sagat, Long Island City, N. Y.

Application May 15, 1946, Serial No. 669,961

6 Claims. (Cl. 46—204)

1

This invention relates to mechanically driven toys and more particularly to toys which are propelled by the wagon or carriage which conveys them over a surface, such as a wagon or device adapted to be pushed and having a whirligig device connected by a belt or other drive means to the wheel axle of the carriage to effect its operation.

It is an object of the present invention to provide a whirligig device having two devices mounted on a common shaft and adapted to be driven in opposite directions.

It is another object of the invention to provide a whirligig device with a bell arrangement adapted to operate on each revolution of one of the whirligig devices and wherein means is provided without the removal of the bell and by a simple adjusting operation whereby the bell noise can be muffled.

According to the invention, a wagon type carriage is provided with pairs of front and rear wheels. This carriage is provided with a vertically extending bracket carrying at its upper end a shaft. At the opposite ends of the shaft and sides of the wagon, there is mounted for rotation thereon two different forms of whirligig devices, one of which may take the form of a Ferris wheel and the other may be a sliding block wheel. Each of these devices has a pulley and is respectively independently connected to a pulley on the rotating rear axle shaft to effect the operation of the devices as the wagon is pulled over a surface. One of the belts is preferably crossed to give a reverse rotation to the one device to which the belt is connected.

On the same shaft is a sleeve for carrying a belt which is suspended downwardly therefrom and adapted to be struck on each revolution of one of the devices. The sleeve is disposed on the shaft between the devices and adapted so that one end can be slid into frictional engagement with one device and thereby be rotated in a reverse direction until it is struck and returned to its starting position by the striker on the other device. Since the bell is moved toward the oncoming striker, it is thrown into a position with reference to the sleeve which carries it so that the bell makes little noise. The child may be led to believe that the bell is being struck at its highest capacity if the adjustment is given before the toy is presented to the child. A simple adjusting screw forces the sleeve toward frictional engagement with the one device. This adjusting screw is carried concentrically with the shaft and extends through the other device for

2

engagement with the end of the sleeve opposite to the end which has frictional engagement with the one device.

For further comprehension of the invention, and of the objects and advantages thereof, reference will be had to the following description and accompanying drawings, and to the appended claims in which the various novel features of the invention are more particularly set forth.

10 In the accompanying drawings forming a material part of this disclosure:

Fig. 1 is a perspective view looking upon the wagon containing the whirligig arrangement embodying the features of the present invention.

15 Fig. 2 is a cross sectional view in elevation taken through the wagon, looking directly upon the whirligig devices along line 2—2 of Fig. 1.

Fig. 3 is a top plan view of the toy.

Fig. 4 is a bottom plan view of the wagon.

Fig. 5 is a rear elevational view of the wagon.

Fig. 6 is a side elevational view of the wagon.

15 Fig. 7 is an enlarged fragmentary view, in cross section taken through the friction retaining means for the bell sleeve and the adjusting knob 25 for effecting the tightening movement of the sleeve for frictional engagement with the one whirligig device.

20 Fig. 8 is a cross sectional view taken through the bell sleeve on line 8—8 of Fig. 7, looking in the direction of the arrows thereof.

25 Referring now to the figures, the invention generally comprises a wagon 10, a vertically extending bracket 11 on the wagon, a shaft 12 extending transversely of the upstanding bracket 11, a Ferris wheel device 13 on one end of the shaft and a sliding block device 14 at the opposite end of the shaft, a bell device 15 disposed between the two devices on the shaft to be operated by the Ferris wheel devices against which it is held by an adjustment of an adjusting sleeve or screw 16 carried by the sliding block device 14. The Ferris wheel device 13 is mounted for rotation on the shaft 12 while the sliding block device 14 is fixed to the shaft 12 to rotate therewith. A pulley 18 is connected rigidly with the shaft 12 so as to rotate the shaft and sliding block device 14. A crossed belt 19 connects the pulley 18 with a pulley 21 fixed to the rear axle shaft 22 driven by rear wheels 23.

30 A pulley 24 is connected rigidly with the Ferris wheel device 13 and receives its power by way of a belt 25 which extends over a pulley 20 fixed to the rear axle shaft 22 at the opposite side of the wagon. The wagon 10 has a front wheel carriage 26 for supporting the forward end there-

of and for effecting steering movement as the toy is pulled and steered by a handle 27. A guard rail 28 is mounted on the peripheral top edges of the wagon floor 29 and serves to retain other articles placed on the floor 29 at the front thereof from falling off as the wagon is pulled.

The upstanding bracket 11 is of U-shaped construction and secured by its intermediate arm to the wagon floor 29 by screws 31. The upper ends of the arms of the U-shaped bracket support the shaft 12 which is retained against axial displacement by securing nuts 32 and 33. The shaft 12 rotates in the upper ends of the arms of the U-shaped bracket.

The Ferris wheel structure 13 has the usual seats 34 pivoted between vertically-extending side wheel portions 35 and 36. The pulley 24 is carried on the side wheel portion 35 by a hub 37 formed on the wheel portion 35. On the side wheel structure 36 and immediately surrounding the shaft 12 there is mounted a disc 39 of friction material; for example, rubber, adapted to have the end surface 41 of the bell supporting sleeve 42 clamped thereagainst by the adjusting sleeve 15 or screw 16 of the sliding block device 14. The adjusting sleeve 16 has an externally-threaded portion 44 threadedly engaging the internal threads 45 of a hub 43 of the sliding block device 14.

The hub 43 is normally fixed to the shaft 12 by a set screw 46 accessible through a hole 47 in the hub 43. The set screw also passes through an opening 48 formed in one side of the adjusting sleeve or screw 16. The opening is of a size larger than the diameter of the set screw 46, see Fig. 7, permitting rotation of the adjusting sleeve or screw 16 to engage the end of the bell supporting sleeve 42, as shown at 49 in Fig. 7, and urge the sleeve into facial contact with the friction disc 39 carried by the Ferris wheel structure 13. When in this position friction between the sleeve 42 and the disc 39 will be greater than the friction between the sleeve 42 and the end of the adjusting sleeve or screw 16 and the sleeve 42 will be turned by the friction disc 39 while the latter surfaces will slip over each other. The adjusting sleeve or screw 16 can only be adjusted until the walls of the opening 48 strike the set screw 46, but this is sufficient to achieve the desired adjustment of the sleeve 42 against the friction disc 39. Normally, the sleeve 42 is free on the shaft 12 and supported in such a fashion that the bell hangs directly under the sleeve. If friction connection is made with the wear surface 39 by the sleeve 42, as when the adjusting sleeve or screw 16 is turned, the sleeve 42 will be rotated by the Ferris wheel device 13 and the bell 51 will be lifted by its stem 52 to substantially a horizontal position where it will be retained by its own weight and the end of the sleeve 42 will then slide on the friction disc 39. A striker 53 rotating in the opposite direction with the sliding block device 14 will strike the bell 51 returning it to its depending position causing the sleeve 42 to slide on the friction disc 39. When the full line position of Fig. 8 is reached, the bell will be free to pivot and the striker 53 will then pivot the bell and move past the bell freeing it to again be raised to the substantially horizontal position to again be struck and lowered by the striker 53. The bell 51 can pivot relative to its stem 52. Due to the slippage between the sleeve and the wear surface resulting from the weight of the bell when disposed in a horizontal position at one side of the sleeve, the bell will be generally retained in that position

and as indicated at 54 (Fig. 8), will be more or less muffled as the top of the bell 51 will be in contact with the sleeve 42, as indicated at 55, see Fig. 8. The muffling will be effected because of the contact of the bell 51 with the peripheral surface of the sleeve 42. The bell will take the position shown at 54, if wagon carrying the Ferris wheel device and the sliding block device is pulled in a forward direction. If the wagon is pushed in a rearward direction, the bell 51 will be located at the opposite side of the sleeve 42 as indicated at 56, see Fig. 8.

The sliding block device 14 has a series of radial spoke arms 58 which extend from the hub 43, and the outer end of each spoke arm is provided with a stop 59. A block 61 is slidable on each spoke arm 58 between the hub 43 and the respective stop 59. The blocks 61 are adapted to slide outwardly on the spoke arms 58 as they pass from a horizontal position to a downward position and to move inwardly on the spoke arms as they move from a horizontal position to an upward position.

A striker 62 may be disposed on the Ferris wheel device for operation of the bell by the device, when the adjusting sleeve or screw 16 is retracted relieving the pressure on the sleeve 42 which holds the sleeve 42 in contact with the friction disc 39. The sleeve will then be idle on the rotating shaft 12 and the bell 51 will be depended downwardly to be successively struck by the strikers 53 and 62.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A whirligig toy comprising a wagon carriage having a rotating rear axle, an upstanding bracket on the wagon carriage, a shaft on the upper end of the upstanding bracket, a rotating device mounted for rotation on said shaft, another rotating device mounted for rotation with the shaft, means connecting the devices to the rotating rear axle to effect the rotation of the devices respectively in opposite directions, and a bell device carried by the shaft between the two devices and adapted to be rotated by one of said rotating devices and struck by the other of said devices.

2. A whirligig toy comprising a wagon carriage having a rotating rear axle, an upstanding bracket on the wagon carriage, a shaft on the upper end of the upstanding bracket, a rotating device mounted for rotation on said shaft, another rotating device mounted for rotation with the shaft, means connecting the devices to the rotating rear axle to effect the rotation of the devices respectively in opposite directions, a bell device carried by the shaft between the two devices and adapted to be rotated by one of said rotating devices and struck by the other of said devices, said bell device including a sleeve axially slidable along said shaft and adapted to be adjusted for frictional engagement with a friction disc on the non-striking device whereby the sleeve and the bell which normally hangs directly under the sleeve is picked up by the said one device and frictionally retained in a position where the bell lies adjacent and in contact with

the sleeve whereby to muffle the sound of the bell upon the same being struck by a striker on the said other device.

3. A whirligig toy comprising a wagon carriage or similar support having a rotating axle, an upstanding bracket mounted on the carriage, a shaft journalled on the upper end of the upstanding bracket, a pulley rigid on the shaft and connected by means of a transmission device for rotation by said axle to rotate said shaft, a device fixed for rotation upon and by the shaft as the same is rotated, a second device journalled on the shaft to be driven by a transmission device connecting the same with the axle, a bell device carried by the shaft between the two rotating devices to be rotated by one of said devices, and a striker carried by the other of said devices for striking said bell device.

4. A whirligig toy comprising a wagon carriage or similar support having a rotating axle, an upstanding bracket mounted on the carriage, a shaft journalled on the upper end of the upstanding bracket, a pulley rigid on the shaft and connected by means of a transmission device for rotation by said axle to rotate said shaft, a device fixed for rotation upon and by the shaft as the same is rotated, a second device journalled on the shaft to be driven by a transmission device connecting the same with the axle, a bell device carried by the shaft between the two rotating devices to be rotated by one of said devices, a striker carried by the other of said devices for striking said bell device, said bell device including a sleeve with a bell suspended therefrom, the sleeve normally being loose to permit the bell to lie suspended beneath the sleeve, a friction disc on the non-striking rotating device, and an adjusting device for forcing the sleeve into frictional engagement with the friction disc, whereby to permit the sleeve to be rotated and retained so that the bell will be held offset from its normal position and adjacent to the surface of the sleeve so that the striker will fail to give a ringing effect to the bell.

5. A whirligig toy comprising a wagon carriage having a rotating rear axle, an upstanding bracket on the wagon carriage, a shaft on the upper end of the upstanding bracket, a rotating device mounted for rotation on said shaft, another rotating device mounted for rotation with

the shaft and means for connecting the devices to the rotating rear axle to effect the rotation of the devices respectively in opposite directions, a bell device carried by the shaft between the two devices to be rotated by one of said rotating devices and be struck by the other of said rotating devices, said bell device including a sleeve with a bell suspended therefrom, the sleeve normally being loose to permit the bell to lie suspended beneath the sleeve, a friction device on the rotating device which rotates said bell device, and an adjusting device for forcing the sleeve into frictional engagement with the friction disc, whereby to permit the sleeve to be rotated and retained so that the bell will be held offset from its normal position and adjacent to the surface of the sleeve so that the rotating device which strikes the bell device will fail to give a ringing effect to the bell, said adjusting device comprising a threaded adjusting sleeve surrounding the shaft and extending through the said other rotating device for adjustment into engagement with the end of the bell supporting sleeve, and means for securing the said other rotating device against axial displacement while said adjusting sleeve is being rotated.

6. A pull toy, comprising a floor, an axle mounted to turn on the floor, ground wheels mounted on the ends of the axle to turn the same on engagement with the ground, a bracket mounted on the floor and having vertically extending arms, a shaft mounted to turn on the vertical arms, a Ferris wheel mounted to turn on the shaft, means for rotating the Ferris wheel from the axle, a sleeve mounted on the shaft to make frictional contact with one side of the Ferris wheel, a sliding block device mounted to rotate with the shaft, said sliding block device having a plurality of radial spoke arms provided with stops at their outer ends, a block slidable on each of said spoke arms and engageable with the stop thereof, a bell mounted on said sleeve, a striker carried by the sliding block device, means for rotating the sliding block device and shaft in a direction opposite to the direction of rotation of the Ferris wheel, and means on said sliding block device for holding said sleeve in frictional engagement with the Ferris wheel to be rotated thereby.

MICHAEL SAGAT.
